US00D631601S

(12) **United States Design Patent**
Lodhie

(10) **Patent No.:** **US D631,601 S**
(45) **Date of Patent:** ** *Jan. 25, 2011

(54) **LED LIGHT MODULE WITH CUTOUTS**

(76) Inventor: **Pervaiz Lodhie**, 23105 Kashiwa Ct.,
Torrance, CA (US) 90505

(**) Term: **14 Years**

(21) Appl. No.: **29/356,312**

(22) Filed: **Feb. 23, 2010**

Related U.S. Application Data

(63) Continuation of application No. 29/318,604, filed on
Jun. 10, 2008, now Pat. No. Des. 613,886.

(51) **LOC (9) Cl.** **26-99**

(52) **U.S. Cl.** **D26/122; D26/118**

(58) **Field of Classification Search** D26/1,
D26/24, 67, 68, 71, 72, 80, 118, 120-122;
362/249.02, 249.03, 249.06, 294; 438/28

See application file for complete search history.

(57) **CLAIM**

The ornamental design for a LED light module with cutouts,
as shown and described.

DESCRIPTION

FIG. 1 is a perspective view of the LED light module with
cutouts showing a first embodiment of the design;

FIG. 2 is a right side view thereof.

FIG. 3 is a left side view thereof.

FIG. 4 is a front view thereof.

FIG. 5 is a back view thereof.

FIG. 6 is a top view thereof.

FIG. 7 is a bottom view thereof.

FIG. 8 is a perspective view of the LED light module with
cutouts showing the design of FIG. 1 with both the back plate,
and claimed portions thereof being removed for illustrative
purposes only;

FIG. 9 is a side view thereof showing the design mounted on
a street post;

FIG. 10 is a perspective view of the LED light module with
cutouts showing a second embodiment of the design; and,

FIG. 11 is a perspective view of the LED light module with
cutouts showing the design of FIG. 10 with both the back
plate, and claimed portions thereof being removed for illus-
trative purposes only.

The back plate, street post and the housing of the LED light
module with cutouts are all shown in broken lines in the
figures to represent environment only and form no part of the
claimed design.
